UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

GUIDE MEANS FOR WARPERS AND SIMILAR MACHINES.

Application filed May 21, 1923. Serial No. 640,429.

To all whom it may concern:

Be it known that I, ALONZO E. RHOADES, a citizen of the United States, and resident of Hopedale, county of Worcester, and 5 State of Massachusetts, have invented an Improvement in Guide Means for Warpers and Similar Machines, of which the following description, in connection with the accompanying drawing, is a specification, like 10 characters on the drawing representing like parts.

This invention relates to yarn winding machines wherein the yarn is wound upon a core in a cylindrical mass by means of a 15 driven winding drum mounted in parallelism with the core and acting by peripheral engagement with the yarn mass on the core to effect the winding operation.

The invention in its preferred form is 20 particularly designed for a warper wherein the yarn is wound upon a warp beam comprising a core, heads in the form of disks at each end and journals, but it is equally applicable in its broader aspects to any form 25 of yarn winding machine of this type wherein it is desired or necessary to maintain the longitudinal position of the yarn receiver in a relatively fixed position with respect to the frame and the winding drum.

30 The object of the invention is primarily to provide means in combination with the elements of the machine involved which act to prevent longitudinal movement of the yarn receiver relatively to the drum during 35 the winding operation or which act to maintain the yarn receiver during the winding operation in fixed longitudinal position.

In this type of machine there is necessarily a relative bodily transverse movement 40 between the core on which the yarn is wound and the winding drum in order to effect the winding operation and in the warper one of these elements, usually the beam, is journalled in arms hinged or mov- 45 ably secured to the frame so as to allow the beam to swing or move bodily transversely toward and from the drum. The winding drum usually comprises a relatively thin cylindrical iron shell open at the ends and 50 if the longitudinal position of the beam is not maintained fixed the longitudinal movement of the beam due to the longitudinal shifting of its bearings or the yield of the supporting arms allows the ends of the shell 55 of the winding drum to engage and grind

against the heads of the warp beam often injuring or damaging the winding drum. Furthermore, this grinding action often so reduces the length of the winding drum as to prevent the proper pressure being applied to the ends of the cylindrical yarn mass wound on the beam. This is highly undesirable as it results in "soft" yarn at the ends of the mass and unequal tension throughout the yarn mass. 60 65

With this invention the warp beam or other yarn receiver is accurately maintained in a fixed longitudinal position so that during the winding operation and during the transverse movement of the drum or 70 yarn receiver there is no danger of the heads of the warp beam engaging the winding drum. Consequently the winding drum is uninjured and its length maintained. The pressure on the yarn mass is kept uniform 75 throughout and accuracy in the placing of the yarn upon the drum or yarn receiver is insured.

These and other objects and features of the invention will appear more fully from 80 the accompanying description and drawings and will be particularly pointed out in the claims.

In the drawings:

Fig. 1 is a side elevation of a portion of 85 an ordinary type of warper with one head of the warp beam partially broken away and with only those parts shown that are necessary for a disclosure of the present invention; 90

Fig. 2 is a plan view of the construction shown in Fig. 1 with the central portion of the mechanism broken away;

Fig. 3 is a detail chiefly in vertical cross section of one of the brackets and guiding 95 rollers;

Fig. 4 is a front elevation of the bracket and guiding roller shown in Fig. 3.

The invention in a preferred form is herein shown embodied in an ordinary and 100 familiar type of warper and, as the invention is only concerned with a specific feature of the operation of the warper, it is only necessary to illustrate and describe those features of the warper directly concerned 105 with the invention.

This type of warper comprises a frame including vertical side members 1 and 2 which support the various shafts and other parts of the warper. The yarn receiver, 110

which in this case is a warp beam, comprises a cylindrical core 3 on which the yarn mass is wound, journals 4 projecting at each end of the core, and generally flat or disk-shaped heads 5. These heads on the interior oppositely facing surfaces are flat and on the exterior surfaces are generally ribbed and braced as illustrated. The journals of the warp beam are usually mounted in bearings 6 formed in the ends of arms 7 movably mounted on the frame. These arms allow the warp beam to move transversely or swing toward and from the frame. The warper beam is a very heavy structure as the heads are made of cast iron or steel and the heavy mass of yarn wound thereon greatly increases the total weight supported in the journal bearings.

The winding drum usually comprises an iron cylinder 8 having a central shaft presenting the journals 9 mounted in bearings 10 on the frame. The drum shaft extends parallel to the beam shaft and the drum is rotated in the usual manner. The periphery of the drum rests against the yarn mass on the core of the beam and thus acts to effect the winding operation, the beam swinging or moving transversely away from the drum as the operation proceeds. While the relative transverse movement which takes place between the winding drum and the yarn receiver is, in the illustrated case, secured by the transverse bodily movement of the yarn receiver, it will be understood that the present invention in its broader aspects is independent of the manner in which this transverse relative movement is secured. Furthermore, while the yarn receiver is illustrated as a warp beam having heads, the particular form of the yarn receiver is not important in the broader aspects of the invention.

In the preferred construction illustrated the fixed longitudinal position of the yarn receiver is secured and thus longitudinal movement with respect to the frame and the winding drum is prevented by means of anti-friction rollers mounted at opposite sides of the frame and having positioning engagement with the yarn receiver, and in this case with the heads thereof, during the winding operation or during the relative transverse movement of the yarn receiver and drum. For this purpose brackets 11 are mounted at each side of the frame. As illustrated, each bracket comprises a foot 12 provided with a longitudinal slot 13 by means of which the bracket is supported on the cap 14 of the journal bearings 10 and held in longitudinal adjustment by the usual bolt 15 which secures the cap to the base of the journal bearings 10. Each bracket rises vertically and then extends outwardly toward the side of the frame in the form of an oblique plate 16. At the outer end of

plate 16 is secured a stud 17 projecting upwardly at right angles to the plate 16 or at an acute angle to the vertical. An annular shell 18 projects upwardly from the plate 16 concentrically with the stud 17. The guiding or anti-friction roller 19 is journaled on the stud 17 and has a shank 20 extending into the chamber formed between the stud 17 and the shell 18. The roller is held in place by any suitable means such as a cotter pin 21 passing through the upper end of the stud.

The upper end of the roller 19 presents an annular chamber 22 having a conical bottom surface 23 extending upwardly toward the stud and, preferably at its center, extending downwardly toward the stud to form the small concentric recess 24. An annular inwardly projecting flange 25 partially incloses the chamber 22 at the top. This construction of the upper end of the roller is provided to prevent oil used in lubricating the roller on the stud 17 from being thrown out or passing from the bearing onto the yarn receiver or warp beam or onto the yarn wound thereon. Great damage might be done to the yarn if the oil got onto the yarn or got onto the beam and therefrom onto the yarn. In the present construction any oil is either caught between the shell 18 and shank 20 or is caught in the chamber 22 and guided back onto the stud. The small concentric recess 24 enables the oil readily to be applied to the stud and also assists in directing the oil caught in the chamber 22 back onto the stud.

The winding drum 8 is preferably constructed in the usual manner so that the outer iron shell presents between itself and the journals 9 at each end a recess in the end of the drum. By mounting the brackets 14 on the bearing caps the substantial portion of the brackets and of the anti-friction rollers are mounted in the recess of the drum so that the peripheries of the rollers only project slightly beyond the ends of the drum as shown in Fig. 2.

The operation of the device is apparent. The brackets 14 are adjusted longitudinally so as to allow the peripheries of the anti-friction rollers 19 to project equally and slightly beyond the ends of the winding drum and in positioning engagement with the inner surface of the beam heads. They should not be so adjusted as to bind upon the heads, and slight play may be allowed so long as the positioning engagement is such as to prevent the beam heads from contacting with the drum during the winding operation. As the drum is rotated, the heads engage and rotate the anti-friction rollers 19 without impeding the rotation of the drum, and as the beam slowly swings or moves away from the drum its longi-

tudinal position is maintained with a minimum amount of friction.

It will thus be seen that the invention 5 obviates the difficulties heretofore encountered and insures the accurate longitudinal position of the beam or yarn receiver with respect to the winding drum and the frame at all times.

Having thus described the invention, what 10 is claimed as new and desired to be secured by Letters Patent, is:

1. A yarn winding machine comprising a frame, a pair of aligned bearings supported and transversely movable on the frame, a 15 yarn receiver having a core and journals mounted in said bearings, a winding drum mounted on the frame in parallelism with the core and acting by peripheral engagement with the yarn mass on the core to effect the winding operation, and means supported on the frame against movement both transversely and longitudinally of the frame and acting to prevent longitudinal movement of the yarn receiver relative to the 20 drum during the winding operation.

2. A yarn winding machine comprising a frame, a pair of aligned bearings supported and transversely movable on the frame, a 25 yarn receiver having a core and journals mounted in said bearings, a winding drum mounted on the frame in parallelism with the core and acting by peripheral engagement with the yarn mass on the core to effect the winding operation, and means 30 mounted at each side of the frame against movement both transversely and longitudinally of the frame and having positioning engagement with the yarn receiver and acting to prevent longitudinal movement of the 35 yarn receiver relatively to the drum during the winding operation.

3. A yarn winding machine comprising a frame, a pair of aligned bearings supported and transversely movable on the frame, a 40 yarn receiver having a core and journals mounted in said bearings, a winding drum mounted on the frame in parallelism with the core and acting by peripheral engagement with the yarn mass on the core to effect the winding operation, and means supported from the frame against movement both transversely and longitudinally of the frame and having positioning engagement with the 45 yarn receiver and acting to maintain it during the winding operation in fixed longitudinal position.

4. A yarn winding machine comprising a frame, a yarn receiver having a core, a winding drum in parallelism with the core and 50 acting by peripheral engagement with the yarn mass on the core to effect the winding operation, a set of journal bearings for the yarn receiver and a set of journal bearings for the winding drum both carried by the 55 frame, one set of said bearings being mov-

able transversely relatively to the other set to permit transverse separation of the core and drum as the winding operation proceeds, and means supported on the frame against movement both transversely and 70 longitudinally of the frame and acting to prevent longitudinal movement of the yarn receiver relatively to the drum during the winding operation.

5. A yarn winding machine comprising a 75 frame, a yarn receiver having a core, a winding drum in parallelism with the core and acting by peripheral engagement with the yarn mass on the core to effect the winding operation, a set of journal bearings for the 80 yarn receiver and a set of journal bearings for the winding drum both carried by the frame, one set of said bearings being movable transversely relatively to the other set to permit transverse separation of the core and drum as the winding operation proceeds, and means supported from the frame having positioning engagement with the element journalled in the transversely movable set of bearings and acting to prevent longitudinal movement of the said element relatively to the other element during the winding operation.

6. A warper comprising a frame, a warp beam having a core, heads and journals, a 95 pair of aligned bearings for the beam journals supported and transversely movable on the frame, a winding drum mounted on the frame in parallelism with the core and acting by peripheral engagement with the yarn mass on the core to effect the winding operation, and means mounted at each side of the 100 frame having positioning engagement with the beam heads and acting to prevent longitudinal movement of the beam relatively to the drum during the winding operation.

7. A warper comprising a frame, a warp beam having a core, heads and journals, a pair of aligned bearings for the beam journals supported and transversely movable on the frame, a winding drum mounted on the frame in parallelism with the core and acting by peripheral engagement with the yarn mass on the core to effect the winding operation, brackets mounted at each side of the 115 frame, and anti-friction rollers journalled on said brackets and having positioning engagement with the surfaces of the heads during the transverse movement of the beam and acting to maintain the beam during such 120 movement in fixed longitudinal position.

8. A warper comprising the construction defined in claim 7 in which the drum is recessed at its ends and in which the brackets and rollers are located substantially within said recesses with the peripheries of the rollers protruding slightly therefrom.

9. A warper comprising the construction defined in claim 7 in which each bracket is provided with a stud projecting upwardly 130

at an acute angle and an annular shell surrounding the bracket and in which the anti-friction roller is journalled on the stud and has a shank extending 5 into the chamber formed between the stud and shell, the upper end of the roller presenting an annular chamber having a conical bottom surface extending upwardly toward the stud and an annular inwardly 10 projecting flange partially inclosing the

chamber at the top, whereby any excess of the oil lubricating the bearings of the roller on the stud is retained in the roller chamber and prevented from reaching the outer surface of the roller and thus from passing onto 15 to beam or the yarn.

In testimony whereof, I have signed my name to this specification.

ALONZO E. RHOADES.
